UNITED STATES PATENT OFFICE.

GEORGE W. PACKER, OF ROCK FALLS, AND CHARLES M. GRIM, OF PIERCEVILLE, ILLINOIS.

HARVESTER.

SPECIFICATION forming part of Letters Patent No. 323,954, dated August 11, 1885.

Application filed April 28, 1884. (No model.)

To all whom it may concern:

Be it known that we, GEORGE W. PACKER, and CHARLES M. GRIM, citizens of the United States, residing, respectively, at Rock Falls and Pierceville, in the counties of Whiteside and De Kalb and State of Illinois, have invented certain new and useful Improvements in Harvesters; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Our invention has reference to harvesters; and it consists more especially of certain novel mechanism by which the machine can, at the will of the operator, be automatically raised or lowered simultaneously upon its two carrying-wheels.

As the several parts of a harvester and their inter-relation are well known, we do not consider it necessary to show or describe more than our improvements and their mode of attachment and operation.

In the drawings, Figure 1 is a plan of that portion of a harvester embodying our invention. Fig. 2 is a longitudinal section in the line $x-x$ of Fig. 1, with a portion of the beam G^5 broken away. Fig. 3 is a side elevation of the grain-wheel and its adjacent parts, with the wheel B broken away. Fig. 4 is a detached view of the location and attachment of the lever which actuates the clutch I .

A is the inner carrying-wheel, which revolves loosely on its axle A' and drives the machinery.

B is the grain-wheel.

D is a transverse shaft, on the inner end of which is rigidly attached a spur gear-wheel actuated by an internal gear on the inside of the rim of the wheel A . On the outer end of the shaft D is rigidly affixed the bevel-gear D' , which engages the bevel-gear E , fixed on the shaft E' , the front end of which shaft actuates the sickle, and on the rear of which shaft is fixed the sprocket-wheel F , which latter, by means of the sprocket-chain F' ,

operates the roller F^2 , which carries the outer end of the revolving grain-platform. The chain F' , midway, passes over and rotates the sprocket-wheel G , which rotates loosely on the shaft G' , the latter being suitably journaled on the frame of the machine.

H is a bevel-gear on the inside of and integral with the sprocket-wheel G . The bevel-gear H meshes with and rotates the bevel-gear H' , loosely journaled on a stud, H^2 , suitably attached to the frame of the machine at right angles to the shaft G' . The bevel-gear H' in turn engages and rotates a third bevel-gear, H^3 , loosely placed on the shaft G' , so that in the onward motion of the machine the sprocket-wheel G and bevel-gears H , H' , and H^3 continually revolve, while the shaft G' is arranged to rotate at intervals, as hereinafter described.

I is a clutch feathered on the shaft G' , between the bevel-gears H and H^3 , and provided at each end with a ratcheted edge fitted to engage a corresponding ratcheted edge formed on the adjacent ends of the gears H and H^3 . The clutch I is so feathered on the shaft G' that it may be moved longitudinally on such shaft. The interval between the gears H and H^3 on the shaft G' is such that when the clutch I is midway between such gears it will engage neither, and the shaft G' will remain stationary; and it is obvious that when the clutch I is moved far enough to engage the gear H the latter will rotate the shaft G' in one direction, while if such clutch is made to engage the gear H^3 , the latter will cause the shaft G' to rotate in the opposite direction.

K is a horizontal arm pivoted near its center to the frame of the machine, and fitted at its outer end to clasp and slide the clutch I into engagement with either the gear H or gear H^3 . The arm K is oscillated at the will of the operator by means of a vertical lever, K' , fulcrumed on the upper part of the frame of the machine, so as to be oscillated forward or backward in the line of the progress of the machine. The lower end of the lever K' is inserted in the inner end of the arm K , and by means of such lever the operator can throw the clutch I into engagement with either of the bevel gears H or H^3 , or hold such clutch

midway between such gears and out of engagement with either. Near its front end the shaft G' is provided with a screw or worm, G^2 , which meshes with a spur-gear, G^3 , located beneath such worm G^2 , and loosely pivoted on the stud G^4 , attached to the outer face of the beam G^5 , forming part of the frame of the machine.

Integral with and inside the gear G^3 is provided a sprocket-wheel, G^6 , which actuates a sprocket-chain, M , which latter in turn passes around and rotates a sprocket-wheel, N , rigidly fixed on the axle A' , which axle revolves independently of the wheel A , intermittently, as hereinafter described.

On the axle A' is keyed a small spur-pinion, N' , fitted to engage an upright rack, N^2 , rigidly fastened on the inner face of the beam G^5 and furnished with the inner gear-face, N^3 . The rotation of the pinion N' by means of the shaft G' , worm G^2 , gear G^3 , and sprocket-wheel N , and axle A' causes such pinion N' to traverse the gear-face N^3 either upward or downward, contingent upon the direction of the rotation of the shaft G' . The axle A' of the drive-wheel A has a similar pinion, N' , at its inner end, which engages a similar rack, N^2 , on the beam G^5 . When the pinions N' are rotated so as to pass upward on the gear-faces N^3 , the machine is lowered, and when the pinions N' pass downward in such gear-faces N^3 the machine is raised.

To prevent accidents resulting from too prolonged rotation of the pinions N' , spaces are left in the bottoms of the racks N^2 , below the gear-faces N^3 , which, when the pinions N' enter them, permit such pinions to rotate without affecting the altitude of the machine; but the gear-faces N^3 are so long that the pinions N' would not be permitted to reach the lower ends of such gear-faces save through inadvertence or negligence in the operator.

At the upper end of the rack N^2 , Fig. 2, is located a trip, O , of bell-crank lever form, pivoted at its center to the side of such rack and having its inner or free end placed so as to be forced upward by the pinion N' when the latter has advanced to near the upper end of the gear-face N^3 . This action moves the outer end of the trip O backward, and such outer end of the trip O is connected, by means of the rod O' , to the arm K , between the fulcrum of the latter and the point of its engagement with the clutch I , and when thus moved forces such clutch out of engagement with the bevel-gear H^3 and stops the further revolution of the shaft G' , and consequently stops the further revolution and vertical progress of the pinions N' .

The connection of the rod O' with the lever O is formed by inserting the upper end of the rod O' in the hole h in the outer end of the lever O , and placing on such rod a rigid collar, O^2 , so located that the lever O will strike such collar when the clutch I is in engagement with the bevel-gear H^3 ; but as the rod O' can be

freely moved farther to the rear by withdrawing partially from the hole h , it permits the clutch I to be thrown into gear with the bevel-gear H^3 in the manner before described.

It will be observed that it is the engagement of the clutch I with the bevel-gear H^3 which rotates the pinions N' in the direction to cause them to climb the gear-faces N^3 .

The shaft G' at its rear end is fitted to receive a crank, G^7 , by means of which such shaft can be rotated and the machine raised or lowered when stationary.

The foregoing description has been confined to the construction and operation of the parts involved in raising and lowering the inner end of the machine.

We will now proceed to describe the mechanism employed in raising and lowering the outer or grain end of such machine.

P is a strong chain, the end link or ring of which encircles the axle A' between the sprocket-wheel N and the pinion N' , Fig. 2. The chain P is passed upward and outward over a pulley, b , suitably journaled on the plate e , attached to the inner face of the beam G^5 , and from thence passes downward and outward under a pulley, d , journaled on the plate e , attached to the outer face of the beam G^5 , the lower edge of the pulley d being slightly below the plane of the bottom of the platform of the harvester. From thence the chain P passes transversely under the center of such platform to the outer side of the machine, Fig. 3, under a pulley, f , journaled in the lower end of a yoke, S , fastened vertically to the outer face of the beam T and forming part of the frame of the machine. The yoke S is provided with a vertical slot, S' , in which is placed, on suitable ways, g , a plate, V , so that such plate V may move freely up and down in such slot. On the outer face of the plate V is formed integrally with such plate the horizontal stud V' , which is the axle or spindle of the wheel B . The chain P , after passing as aforesaid under the pulley f , passes upward behind the plate V and between the latter and the beam T , and is attached to such plate near the upper end thereof, in a slot, a , in the upper end of such plate. It is obvious that when the chain P is drawn upon by the pinions N' passing down the gear-faces N^3 , such chain has the tendency to draw the plate V downward toward the pulley f , and this upward pressure on the pulley f forces the yoke S and beam T upward, at the same time drawing the plate V and stud V' downward, which, as it moves the axle of the wheel B downward relatively to the frame of the machine, has the effect of thus raising the latter. When the pinions N' pass up the gear-faces N^3 , and thus slacken the chain P , the yoke S and outer frame of the machine attached thereto settle downward correspondingly, the pressure upward of the wheel B forcing the plate V upward in the ways g in the yoke S . Thus the action at the inner end of the machine in changing the elevation of the lat-

ter is communicated instantly to and accompanied with corresponding elevations and depressions at the outer end of the machine.

The change of elevation of the machine while the latter is in motion is a necessity caused by the varying height of the grain and occasional lodged or fallen areas. To make such changes automatically is quicker and involves less labor than by hand, and in addition it has been almost impracticable to raise both ends of a harvester simultaneously by hand, and the raising one end alone would throw the machine out of shape.

The axle A' has a fixed and unvarying altitude, regardless of the height of the cut of the machine, and the advantage attained by collaring the end of the chain P on such axle is, that the machine is raised or lowered in precisely the same degree from its two fixed or carrying points, whatever may be the pitch or inclination of the parts in front and rear of the line between such points. Such points are also intended to be in the lateral line of the center of gravity of the machine, and the draft of the chain P does not tend to oscillate the machine on its carrying-axles, as would be the case were the points of attachment of the chain in front or in rear of such axles.

What we claim as our invention, and desire to secure by Letters Patent of the United States, is—

1. The combination of the bell-crank lever O, clutch I, rod O', and the collar O² upon the rod O', whereby such rod can be partially

withdrawn from such lever, to permit the engagement of the clutch I with the gear H, substantially as shown, and for the purpose mentioned.

2. The combination of the rack N², pinion N', lever O, rod O', and clutch I, such rod O' being provided with a collar, O², substantially as shown, and for the purpose named.

3. The combination of the axle A', pulleys b and d, chain P, yoke S, provided with the pulley f, the plate V, stud V', beam T, and wheel B, substantially as shown, and for the purpose specified.

4. In combination with the axle A, the chain P, loose collared at one end on said axle and passing transversely under the grain-platform, and attached at its opposite end to a vertically-sliding plate, V, and means for operating the chain, whereby the inner and outer sides of the machine are simultaneously raised and lowered, substantially as described.

5. The combination of the yoke S, rigidly attached to the outer side of the frame, the plate V, adapted to slide vertically in said yoke, and the chain P, substantially as shown, and for the purpose specified.

In testimony whereof we affix our signatures in presence of two witnesses.
